UNITED STATES PATENT OFFICE.

EDWARD J. STONE, OF DULUTH, MINNESOTA; BURNICE E. STONE SOLE LEGATEE AND DEVISEE OF ESTATE OF SAID EDWARD J. STONE, DECEASED.

PILE-DRIVER HAMMER.

Application filed June 12, 1922. Serial No. 568,065.

To all whom it may concern:

Be it known that I, EDWARD J. STONE, a citizen of the United States, residing at Duluth, in the county of St. Louis and State of Minnesota, have invented certain new and useful Improvements in Pile-Driver Hammers.

My invention relates to pile driver hammers, and has for its object the provision 10 of a hammer equipped with elastic lifting or suspending means, whereby the strain of lifting the hammer is gradually applied and the wear and tear on the suspending sheaves, leads, and hoisting engine is greatly reduced. 15 It consists of the constructions, combinations and arrangements of parts hereinafter described and claimed.

In the drawings, Fig. 1, is a top plan view 20 of a hammer embodying my invention. Fig. 2, is a central vertical section of said hammer. Fig. 3, is a top plan view of the hereinafter described foot plate, and Fig. 4 is a side elevation of said hammer.

In the drawings, 1 is the body portion of 25 a hammer in the opposite sides of which are preferably formed vertically directed grooves 1^a adapted to receive the hammer guides of a pile driver of any suitable structure (not shown). Formed in said hammer 30 is a central vertically directed recess comprising a lower portion or spring chamber 1^b and an enlarged upper portion or casting chamber 1^c. Positioned in said spring chamber, near the lower end thereof, is a foot 35 plate 4 having ears 4^a formed thereon, which ears are adapted to extend into vertically directed guide grooves 1^e formed in the side walls of said spring chamber, whereby said plate is prevented from turning.

Erected upon said foot plate is a helical 40 compression spring 5, extending in normal condition to the upper end of said spring chamber.

Lying in the bottom of the casting chamber and extending over said spring, is a 45 casting 2 against which the upper end of said spring, is adapted to bear. A cup 2^a adapted to hold a Babbitt metal bushing 2^b is preferably formed upon the lower face 50 of said casting and adapted to extend into the upper end of said spring. A bolt 3 headed at its lower end, and preferably of square cross section from its lower end upward for a suitable portion of its length, 55 extends upwardly through a noncircular

central aperture in said foot plate and through said spring and through an aperture in said cup, bushing, and casting. Mounted upon said casting and encircling said bolt is a cushion washer 7 of resilient 60 structure or material, and a non-resilient washer 8, and secured to said bolt in threaded engagement therewith. Above said washers is a nut 6, provided with an eye 6^a adapted to engage a lifting hook or cable (not 65 shown), of any suitable material or structure but forming no part of the present invention.

Extending through said hammer closely above said casting are bolts 9, 9^a adapted to 70 firmly hold said casting down against the upward thrust of said spring. Oil may be applied to the spring recess through any suitable port, as through the port 2^c in said casting, and said recess may be drained 75 through any suitable port as through the port 1^d, the outer end of which may be closed by a plug 1^f. Said hammer may be apertured in any suitable place or places as at 10, 10^a, 10^b, for the purpose of engaging 80 lifting, or handling rods or appliances (not shown), while assembling the apparatus, or if the normal lifting means should break, or upon certain other special occasions.

In operation, the usual lifting tackle (not 85 shown but well known to the art), is engaged with said eye 6^a. The hoisting strain being applied, said bolt 3 is drawn upwardly causing said foot plate to compress said spring which cushions the weight of hammer upon the hoisting apparatus, thus 90 avoiding violent shock to said apparatus. When the weight is released, the bolt and nut and foot plate are retracted suddenly by the expansion of said spring, but are 95 cushioned by said cushion washer.

It is obvious, however, that my invention may be altered or modified in various particulars within the spirit and scope of certain of my claims.

What I claim is:

1. In a pile driver hammer, the combination of a hammer body having a recess formed in its upper end, of a compression spring positioned in said recess, an abutment extending over said spring and secured to said body, a foot plate below said spring, said foot plate being engaged with said body portion to prevent the turning of said plate in a horizontal plane, a single shaft 105 110

bolt extending through said foot plate, spring and abutment a bushing interposed between said bolt and said abutment, said plate being adapted to engage said bolt to prevent said bolt from turning in said plate, and an eye-nut secured to the upper end of said bolt.

2. In a pile driver hammer, the combination with a hammer body having a recess formed therein, of a spring positioned in said recess; an abutment positioned in said recess and extending over said spring; means for securing said abutment in said re-

cess; a foot plate below said spring; a cushion washer above said abutment; a bolt extending through said plate, spring, abutment and washer; and means secured to the upper end of said bolt for transmitting a lifting force thereto.

In testimony whereof, I hereunto affix my signature, in presence of two witnesses.

EDWARD J. STONE.
